AUTOMATIC HEADING DEVICE

Alexander Boynton, San Antonio, Tex., assignor
to Chas. A. Beatty, San Antonio, Tex.

Application October 14, 1932, Serial No. 637,710

10 Claims. (Cl. 103—234)

My invention relates to devices for raising liquid from wells and more particularly to those in which air or other gaseous fluid is employed as a pressure medium to aerate and lift the fluid from the well by the expulsion of liquid slugs therefrom.

It is an object of the invention to provide a simple and effective device for admitting into the eduction tube of a well a slug or column of liquid of a predetermined weight or length, and to then seal off the liquid intake until the charge already admitted has been lifted from the well. I desire to provide means to automatically prevent the admission to the eduction tube of more than the predetermined amount which is to be discharged at one time. It is also an object to provide means whereby the intake opening for the liquid may be operated to open and close abruptly so as to prevent wear and also to economize time in the operation of the device.

It is a further object of the invention to provide means to prevent the entrance of liquid to the pressure fluid inlet pipe while the same is being introduced into the well or while the eduction tube is removed from the well for examination or repair. I desire to provide means to automatically close the lower end of the pressure tube when the eduction tube is raised.

The invention resides particularly in the details of construction whereby the above objects are accomplished and the adjustment of the apparatus provided for, and in the method weighing each slug and providing that each slug shall be of uniform weight or length.

With reference to the drawings herewith, in which a preferred embodiment of the invention is disclosed, Fig. 1 is a central longitudinal section through the upper end of an apparatus embodying my invention.

Fig. 2 is a similar longitudinal sectional view through the well casing and the tubing employed therewith taken at a level below that shown in Fig. 1.

Fig. 3 is a similar view showing a continuation of the apparatus shown in Fig. 2 on the lower side thereof.

Fig. 4 is a longitudinal section through the automatic valve operating device.

Fig. 5 is a transverse section on the plane 5—5 of Fig. 3.

Fig. 6 is a similar transverse section on the plane 6—6 of Fig. 4.

Figs. 7 and 8 are central vertical section and bottom plan view respectively of the ball cage

disclosed in Fig. 4, Fig. 7 being taken on the plane 7—7 of Fig. 8.

Figs. 9 and 10 are top plan and side elevational views respectively of the ball rider employed in connection with said ball cage.

Fig. 11 is an assembly view, partly in section, of the device as it is positioned in the well.

I contemplate employing fluid lift devices in connection with the usual well equipment, including a casing 1, which is ordinarily employed in retaining the walls of the well. At the upper end of the casing I show a casing head 2, having a plurality of lateral ports therein, one of which is shown as being connected with the gas line 3 and the other closed by a bull plug 4. The upper end of the casing head is threaded exteriorly to receive a cap member 5. The interior of the casing head is formed with a seat at 6 to form a seal with a radial plate 7 upon the pressure tube 8 by means of a seal of lead or other soft metal 20 or tight textured fabric 9 fitting between said plate and said seat.

The plate 7 is secured rigidly to the outer periphery of the pressure tube by welding or similar means shown at 10, but parts 7 and 14 may 25 be cast in one piece and screwed on to the pressure tubing. On the upper side of the plate is an annular groove or recess within which is poured or otherwise placed a sealing ring 11 of lead or other soft metal or hard packing material. This 30 ring of sealing material is engaged by a downwardly extending flange 12 upon the cap member 5. It will be noted therefore that when the cap member 5 is screwed down upon the casing head the flange 12 will engage the seal 11 upon 35 the plate 7 and force said plate rigidly down to seal with the lead gasket 9 in the casing head. Furthermore, the lower rim of the flange 12 is adapted to engage against the lead seal 11 and form a further seal at that point. The weight 40 of the tubing assists in compressing the gasket 9, thereby producing a complete seal off at that point with little or no assistance being required from the flange 12 or seal 11. Such packing can 45 not be made of any but soft alloys wholly lacking in the spring element which I supply as a separate part.

The well is equipped with the outer tube 8, which I call the pressure tube, serving as an inlet for the pressure fluid, such as air under pressure, 50 which is delivered to the pressure tube through the lateral line 13. The pressure tube is formed with a coupling 14 thereon which is adapted to contact with the upper sealing plate 7 and more effectively support the pressure tube. Above the 55

inlet line 13 I form a stuffing box or sealing member shown at 15, which forms a seal about the inner eduction tube 16. A collar 17 upon said tube within the stuffing box engages upon a 5 gasket 18 and forms a fluid tight support for said eduction tube. The stuffing box is for the purpose of providing additional sealing means, if the gasket 18 should not seal tight.

The air or gas which is employed as a lifting 10 medium passes downwardly into the well through the passage 19 between the pressure tube and the eduction tube. Adjacent the lower end thereof, the pressure tube is engaged within a swaged coupling member 20. Said coupling is 15 reduced in diameter downwardly and provided with an inner seat 21 upon which the lower end of the eduction tube may rest in operation. A bottom seal 22, comprising a ring of compressible material such as lead, or other similar or suitable 20 material, is fitted about the eduction tube within a recess therein and engages the seat to form a seal closing the passage of pressure fluid beyond this point.

The pressure tube, closed at the lower end, as 25 will be described, may be introduced into the well, and thereafter the eduction tube may be inserted downwardly therethrough.

Below the coupling 20 is secured a length of 30 tubing 23, which is slotted, as shown at 24, to allow the inlet thereto of liquid from the well. This tube forms a cage for a check valve 25. The lower end of the tube is closed by a plug 26, which supports a spiral spring 27, upon which is resiliently supported a valve retaining member 28. 35 The upper end of the said member is concaved to receive the ball valve 25, which is held resiliently upward by means of said spring and support.

The lower end of the eduction tube above the 40 valve is rounded at its lower end to form a seat at 29 against which the ball valve may contact. Above the lower end, the eduction tube is slotted at 30 to allow the entrance thereto of liquid when said tube is projected below the coupling 20. When the tube is raised upwardly to obscure the 45 slotted openings 30 within the coupling, the ball valve may seat against an inner ring 31 at the lower end of the coupling 20 and seal against the entrance of liquid upwardly into the pressure tube.

50 The eduction tube is formed, at a point spaced somewhat above the lower end, with an air intake nipple 33 having lateral openings 34 therein for the admission of air or gas below the slug of liquid in the tube. Below the air intake I have shown a check valve 35, which may be of 55 any preferred construction. This valve is housed within a cage and the valve seat 36 is supported by a check valve swage 37, which is fitted tightly within the eduction tube.

60 Below the check valve is my control device whereby the inlet of liquid to the eduction tube is regulated. This device is housed within the housing 38 as shown in Figs. 2 and 3, and in detail in Fig. 4.

65 The automatic valve operating means is located at the lower end of the eduction tube slightly above the seal 22 formed with the coupling 20. The interior of the tube section is threaded to receive a valve seat member 40 which has an axial passage 41 therethrough for the entering liquid. This passage has flared ends thereto, the upper end 42 forming a seat for the valve member 43.

70 The valve operating device is housed within a 75 cylindrical tube or barrel 44 closed at its upper

end by an adjusting plug 45 and open on its lower end, except for a transverse bar 46 forming a carrier for the valve. This bar is threaded centrally to receive the shank 47 upon the valve 5 48. With reference particularly to Fig. 6, it will be seen that the transverse carrier bar 46 is slideable within a diametrical slot 48 formed in an upwardly projecting sleeve 49 upon the valve seat member 40, called the base holder.

The sleeve upon said valve seat is formed to 10 telescope within the housing 44 and forms an anchor for the bottom end connection 50 engaging at its upper end with the multiple diaphragm or bellows. Thus the connecting member 50 is anchored firmly to the valve seat member 40 by being threaded at 51 within the slotted sleeve or upper end of the base holder 49.

The connecting member 50 is a tubular member threaded on its interior and closed at its lower end by a plug 52 which must make an absolute seal at that end of said member to prevent escape of any fluid whatever. Its upper end is formed with the lower end of the bellows shaped diaphragm 54, it being understood that said connecting member and said diaphragm are secured together by a bond of leak proof solder or welding material 55.

The upper end of the bellows member is likewise soldered at 56 to a connecting ring 57. Said 30 ring has an interior threaded engagement with a head 58 upon the carrier shaft 59. Said head extends over the upper end of the ring 57 and may be secured rigidly thereto by means of a bond of solder or welding 60. Thus there is a 35 hermetical seal at the upper end as well as at the lower end of said bellows member. There is a small duct or passage 61 extending upwardly and laterally in the head to provide a vent from the interior of the diaphragm in its assembly as 40 will be later noted.

The head 58 is secured to the adjacent plug 45 previously mentioned, by means of a lock screw 62 which is extended axially downwardly through said plug and screws within the upper 45 end of said head 58. This lock screw also acts as a swivel connection between the head 58 and the adjusting plug, and when said screw is loosened the plug may be rotated to adjust the same vertically within the housing 44 in an obvious manner.

The bellows member 55 is a multiple diaphragm. Its walls are of thin sheet metal and may be of a plurality of layers of metal forming a wall of sufficient strength and resiliency to 55 withstand particular pressures and uses to which it is subjected. Its corrugations may be ring shaped or may extend in a spiral from one end thereof to the other, either form of bellows diaphragm being contemplated in my invention. 60

Within the bellows the carrier shaft 59 extends axially from end to end thereof and a coil spring 63 is mounted thereon bearing at its upper end against the head 58, and at its lower end against the upper end of the connecting member 50 to 65 which the bellows is secured. Said spring is under compression and tends to hold the bellows member in a predetermined elongated position.

This bellows member is adapted to be affected by fluid pressures exerted against the outer walls 70 thereof and may be contracted longitudinally by increases of pressure. When said pressures are decreased, however, a spring will again elongate the bellows member. In assembling the bellows in position I contemplate filling the in- 75

terior thereof with a noncorrosive lubricating liquid such as glycerine. The bellows will be contracted longitudinally after the glycerine has been placed therein to the maximum extent to 5 which it will be contracted in use. The excess glycerine will find a vent through the passage 61, and when the bellows is again released, air will occupy the position of the excess glycerine which was discharged. The function of the 10 glycerine or other liquid is to prevent undue collapse of the walls of the bellows diaphragm and to resist pressures in excess of those ordinarily encountered.

The connecting member 50 previously referred 15 to, houses a latching device employed in connection with my valve. The lower end of the shaft 59 is extended downwardly into said connecting member. I provide a ball cage 65, the construction of which is best seen in Fig. 7. It 20 has a vertical opening 66 therethrough and it is slotted upwardly from its lower end in order to provide four slots 67 which terminate at their upper ends in a radial opening 68 of somewhat larger diameter than the balls 69 which are to 25 be seated therein. Said cage cooperates with a ball rider 70 shown in Figs. 9 and 10. Said rider is made up of a lower ring, the opening therethrough adapted to fit closely with the extension 71 upon the latching shaft, and it has four upwardly extending arms 72, the upper ends of which are beveled downwardly and inwardly at 30 73 to engage against the balls 69. Said arms 72 extend into the slots 67 in the ball cage; and said carrier and said cage are thus interlocked 35 against relative rotation. The ball rider is held resiliently upward against the balls so as to move them inwardly by means of a spring 74, bearing at its lower end against the closure plug 52. Above the ball cage the connecting member is 40 formed with an inwardly extending flange which fits closely about the extension 71 upon the latching shaft. There are passages 76 longitudinally through the flange to allow the passage of the glycerine into or out of the bellows around the 45 latching device.

There are also longitudinal passages 67' in said ball cage and 72' in said ball rider for the same purpose. The balls are slightly larger than the reduced inner ends of the radial openings 68 to prevent release of said balls when the shaft 50 extension is removed.

In assembling this device, the parts are assembled as shown, the shaft extending downwardly through the ball cage. The parts are then adjusted to determine the latching position of the device and the height of the balls relative to the latching shaft or arm. The shaft extension 71 is then withdrawn and is machined to form an approximately spherical portion 77 thereon which 55 provides latching recesses 78 above and 79 below the straight surface of the same to receive the balls 69. This latching device enables me to operate the liquid inlet valve abruptly. Thus, pressures tending to collapse the diaphragm and 60 force the latch shaft downwardly will be resisted by the balls until the pressure is great enough to move the spherical portion 77 past the balls after which the balls will engage in the upper recess 78, and hold the parts in that position with the valve 43 closed. By operating the valve abruptly 65 in this manner, the wear of the valve and the valve seat when closing or unclosing will be greatly reduced due to the fact that the sudden closing will greatly reduce the passage of abra- 70

sive material between the valve and the seat during the operation.

During the operation of my device the parts 5 will be assembled in the well practically as shown in the drawings. The check valve 25 will be in closed position, while going into the well, to prevent the entrance of liquid therethru so that when the device is ready to operate there will be no head of liquid in the pressure tube to be depressed by the operating air or gas under pressure. The eduction tube will then be lowered into the seat 21 and the projecting end 29 will open the valve 25 to allow entrance of the liquid; as will be observed from Fig. 3. The liquid will 10 rise upwardly past the open inlet valve 43 and into the eduction tube. When the height of the liquid in the tube has reached a predetermined point, the pressure of the head of liquid against the diaphragm will be sufficient to collapse the same to force the latching shaft downwardly 15 past the balls 69 and move the housing 44 and the valve 43 downwardly to close the opening 42 and prevent the entrance of more liquid. Air or gas under pressure will then be introduced 20 down the pressure tubing through the space 19 25 so that it may enter through the openings 34 in the eduction tube and elevate the slug of liquid above the same. The discharge of the air into the well to move the slug of liquid upwardly 30 must preferably be timed so as to allow the entrance of the air only after the liquid inlet has been closed. This may be done by automatic means now known or it may be done manually as preferred.

The check valve 35 is to prevent the exertion 35 of the pressure of the air downwardly upon the producing formation of the well when by chance the liquid inlet valve has not closed as the air is admitted. Ordinarily the check valve will not be necessary when the closing of the inlet 41 by 40 the valve 43 is accomplished before air is admitted into the pressure tubing thus to prevent the passage of the air downwardly into the well.

The amount of air or gas and the pressure at 45 which it should be used, will depend upon the size of the flow tubing, the length of the slug, physical properties of the well liquid, and the depth at which the device is installed.

No pressure used in flowing the well ever contacts the producing formation. Only such part 50 of the well's own pressure is used as may be necessary to force the slug into the tubing; and by adjusting the device to handle short slugs, this pressure may be minimized. As the liquid rises in the flow tubing while the slug is forming, part 55 of its passes out of the flow tubing into the pressure tubing through the air intake holes, and thereby rises to the same level in both flow and pressure tubing. When air is admitted into the pressure tubing this liquid in the pressure tubing 60 is forced back through the air intake holes into the flow tubing. The slug finally formed in the flow tubing and expelled is, therefore, considerably longer than the slug as originally admitted. For example: if the capacity of the flow tubing 65 and the capacity of the annular space between the flow tubing and the pressure tubing should be equal, then the well would force into the flow and pressure tubings a slug only one-half as long as the slug that would be expelled. This fact 70 provides that the internal force of the well (its rock pressure) is conserved. Means which thus provides for expelling a slug twice as long as a well will produce is believed to be entirely new.

Provision is made whereby no fluid enters the 75

pressure tubing as it is lowered or run into the well, and the flow tubing may be lowered into and withdrawn from the pressure tubing at will without allowing fluid to enter the pressure tubing. 5 Were it not for this provision to keep the pressure tubing dry, great pressure would be required to start a well that heads up to a high level. With this provision the first slug is uniform with all others. The well will, therefore, start on the 10 same pressure that will be required to operate it after starting.

If the liquid to be lifted is thin or light, and of a character that allows air or gas to break into or through the slug, a different or heavier liquid, 15 semi-liquid, or gelatinous substance may be admitted into the pressure tubing ahead of each discharge of air or gas into the pressure tubing, thereby to provide that such different or heavier liquid, semiliquid, or gelatinous substance will 20 be forced down the pressure tubing and form a piston-like bottom to or under each slug to prevent or minimize such breaking into or through the slug by the air or gas that expels it.

The valve operating device which I have disclosed is sensitive to fluid pressure, and it will be obvious that an increase of pressure outside the diaphragm will tend to move the walls of the corrugations toward each other so as to collapse the same longitudinally and operate the valve. 30 However, if pressures become excessive the glycerine within the diaphragm will resist the collapse of the same beyond the maximum travel previously determined. The small charge of air in the bellows will be compressed and the liquid will then practically fill the diaphragm and prevent further collapse and injury to the walls thereof.

To illustrate: If the bellows be filled with glycerine to within one inch of the top, and the spring would compress one inch under 100 pounds per square inch applied externally to the bellows, then there would never be more than 100 pounds difference between the external and internal pressures. If then there should be 10,000 pounds per square inch of external pressure there would be 9,900 pounds of internal pressure, leaving a net force of only 100 pounds per square inch acting externally on the bellows. The bellows wall thus becomes impinged between two fluid forces, the external of which can never exceed the internal by more than 100 pounds regardless of how great the external pressure may be. Hundreds of hydraulic compressions up to 5,000 pounds per square inch administered by me to such a bellows assembly, the bellows having a wall thickness of only .008 inch, has never resulted in the slightest damage to the bellows, nor in any way impaired its operation. Hydraulic pressure in excess of 10,000 pounds per square inch frequently has been 40 administered by me to bellows assemblies, the bellows having a wall thickness of approximately .030 inch, with no resulting damage. It being possible to fabricate bellows with wall thickness greatly in excess of .030 inch, it is apparent that this 45 type of construction will safely withstand the highest pressures to be encountered.

I have thus provided a structure which will operate to deliver a predetermined charge of liquid from the well, and the operation thereof may be 50 practically automatic. My valve operating device will allow admission of only a predetermined weight of liquid which can be handled by the air pressures which are contemplated, and the lifting of the liquid by the contemplated fluid pressures 55 will be assured at all times. The device is simple

and efficient in construction and will function with slight wear.

What I claim as new is:

1. In a pneumatic well flowing device, a pressure tube, an eduction tube spaced inside thereof, a seal between said tubes adjacent their lower ends, a constantly open pressure fluid inlet to said eduction tube, a normally open inlet valve for liquid at the lower end of said eduction tube, and means responsive to the weight of liquid above said valve to close said valve when a predetermined load of liquid has passed said valve and to hold said valve closed with increased force as leakage past said valve increases the weight of liquid above it. 10

2. In a pneumatic well flowing device, a pressure tube, an eduction tube spaced inside thereof, a seal between said tubes adjacent their lower ends, a pressure fluid inlet to said eduction tube, a normally open inlet valve for liquid at the lower end of said eduction tube, means responsive to the weight of liquid above said valve to close said valve when a predetermined load of liquid has passed said valve, and releasable means to latch said valve in both open and closed positions. 15

3. In a device of the character described, a pressure tube, an eduction tube spaced inside thereof, means to seal said eduction tube in said pressure tube adjacent the lower end thereof, a liquid inlet to said eduction tube, a valve in said inlet, means connected with said valve to close the same when a predetermined load of liquid has entered said eduction tube, resilient means to resist said closing of the valve and constantly open inlets to said eduction tube for pressure fluid to raise said load of liquid upwardly to the surface. 20

4. In a device of the character described, a pressure tube, an eduction tube spaced inside thereof, means to seal said eduction tube in said pressure tube adjacent the lower end thereof, a liquid inlet to said eduction tube, a valve in said inlet, means responsive to liquid pressure to raise or lower said valve to control the entrance of liquid to said eduction tube, a standing valve in said eduction tube, and inlets for pressure fluid to said eduction tube above said standing valve. 45

5. In a device of the character described, a pressure tube, an eduction tube spaced inside thereof, means to seal said eduction tube in said pressure tube adjacent the lower end thereof, a liquid inlet to said eduction tube, a valve in said inlet, a housing connected with said valve, and a bellows-shaped diaphragm connected with said housing, and responsive to fluid pressures to move said housing and said valve to open and close 50 said valve.

6. In a device of the character described, a pressure tube, an eduction tube spaced inside thereof, means to seal said eduction tube in said pressure tube adjacent the lower end thereof, a liquid inlet to said eduction tube, a valve in said inlet, a diaphragm connected with said valve adapted to be operated by the load of liquid in said eduction tube to open and close said valve and means to latch said valve releasably in both 60 open and closed position.

7. A heading device including an eduction tube, an inlet adjacent the lower end thereof, a normally open valve in said inlet, means automatically operating to close said valve when a predetermined load of liquid has entered said tube including a diaphragm on said valve, a latching shaft in said diaphragm, a spring about said shaft tending to hold said diaphragm extended to hold said valve in open position, means coop- 70

erating with said shaft to hold is releasably in adjusted position, and means to introduce gaseous fluid into or under said liquid to raise it upwardly in said tube.

5 8. A heading device including an eduction tube, an inlet adjacent the lower end thereof, a normally open valve in said inlet, a latch for said valve, means operative by the pressure of fluid in said tube to release said latch and close said 0 valve, and means to introduce gaseous fluid into or under said liquid to raise it upwardly in said tube.

9. A heading device including an eduction tube, an inlet adjacent the lower end thereof, a normally open valve in said inlet, means automatically operating to close said valve when a predetermined load of liquid has entered said tube,

and means in addition to said operating means to accelerate the movement of said valve in both directions, said eduction tube having uncontrolled openings therein through which to introduce gaseous fluid into or under said liquid to raise it upwardly in said tube.

10. A heading device including an eduction tube having inlet openings for pressure fluid, a liquid inlet adjacent the lower end thereof, a valve in said inlet and means including bellows-shaped 10 diaphragm and a releasable latching rod axially thereof to move said valve abruptly to closed position when a predetermined load of liquid has entered said inlet, said means operating to open said valve abruptly when said load has been 15 lifted.

ALEXANDER BOYNTON.
